UNITED STATES PATENT OFFICE.

RAYMOND C. DUDLEY, OF CHICAGO, ILLINOIS.

CAR-ROOF.

1,109,324.

Specification of Letters Patent.

Patented Sept. 1, 1914.

Application filed January 11, 1913. Serial No. 741,382.

To all whom it may concern:

Be it known that I, RAYMOND C. DUDLEY, a citizen of the United States, residing in Chicago, in the county of Cook and State of Illinois, have invented a new and useful Improvement in Car-Roofs, of which the following is a specification.

The invention relates to outside metal car roofs for freight cars, and has for its 10 principal objects to simplify the construction of such roofs, with economy in manufacture, and at the same time to increase the strength, efficiency and durability of the same. And with such objects in view the 15 invention consists in the parts and combinations thereof hereinafter set forth and claimed.

In order to make the invention more clearly understood there are shown in the 20 accompanying drawings means for carrying the same into practical effect, without limiting the improvements, in their useful applications, to the particular constructions which, for the purpose of example, have 25 been delineated.

In said drawings:—Figure 1 is a plan view, partly broken away, of a portion of a car roof embodying the invention. Fig. 2 is an end view of the same. Fig. 3 is a 30 cross sectional view of the same on line III—III of Fig. 1, on a larger scale, and partly broken away. Fig. 4 is a similar view of the central part of the roof, on line IV—IV of Fig. 1. Fig. 5 is a perspective view 35 of the outer end of the seam cap. Fig. 6 is a horizontal section on line VI—VI of Fig. 7. Fig. 7 is a side view of a portion of the car, the running board and its saddle being shown in section. Fig. 8 is a longitudinal, vertical, sectional view of a portion 40 of the car near its end and on line VIII—VIII, of Fig. 2, the running board and saddle being shown in section. Fig. 9 is a vertical transverse section on line IX— 45 IX of Fig. 10. Fig. 10 is a side elevation of a portion of the car, showing additional securing devices for the eaves ends of the roof sheets and seam caps. Fig. 11 is a perspective view of one of the roof sheets. Fig. 12 is a 50 sectional view showing a modified construction of sheet flange and seam cap, combined with the sub-carline.

Referring to the drawings:—1 is the ridge pole of the freight car roof, connected with 55 the side plates 2 by carlines 3. The carlines are or may be of metal of L-shape

(Fig. 1) in cross section extending across the car from one side plate to the other, to which they are secured by bolts 4 passing through flanges 5 formed on the ends of the 60 carlines. The carlines pass beneath the ridge pole, to which they are secured by vertical bolts 6. The top sheathing of the roof is shown at 7 consisting of matched boards running transversely or longitudinally, the latter being the arrangement shown, the sheathing 7 being supported by rafters or any usual or suitable means. The side sheathing is shown at 8, its upper part being attached to the side plates 2 and 70 overlaid by the fascia 9. Connected with the side plates are the end plates 10, carrying the end sheathing 11 overlaid by the end fascia 12. The outer ends of the carlines are formed with horizontal flanges 13 which 75 rest on the tops of the side plates, or in suitable mortises therein as indicated by the dotted line at 13 in Fig. 3; and with vertical flanges 14 which lie on the outer faces of the side plates, thus tying the side plates 80 together and greatly strengthening the roof frame.

The roof sheets 15 (Fig. 11), of sheet metal such as galvanized iron, rest on the top surface of the roof sheathing 7. The 85 outer edge of the roof sheet 15 is formed with a bent down flange 16 having end portions 17 which extend longitudinally of the car beyond the main flat body of the sheet. The side edges are each formed with an upwardly extending L-flange consisting of an upwardly extending part 18 and an outwardly extending part 19. The inner edge of the sheet is formed with a U-flange consisting of an upwardly extending part 20 90 and a downwardly extending part 21. At the inner corners the sheet is properly notched and portions 22 of the flanges are bent around to form water tight corners. The roof sheets 15 are laid side by side along 100 the car on both sides of the ridge, each sheet extending from the ridge to the eaves of the roof. The U-flanges 20, 21 of the contiguous sheets are interlocked with each other at the ridge (Fig. 3) and the flanges 16 lie on 105 the outer surface of the fascia where they are secured by bolts 23 which pass through holes 24 in the flanges and through the fascia and side plates. Some play is however allowed to the roof sheets, the holes 24 being 110 say five-eighths of an inch in diameter and the bolts 23 three-eighths of an inch in diam-

eter. The side flanges 18, 19 of the plates are supported by and embrace supercarlines 25 which rest on the roof sheathing 7 between the vertical flanges 18 of contiguous sheets 5 and extend from ridge to eaves of the roof. At the ridge the supercarlines of the two sides of the roof are mortised together (Fig. 4) and pivotally held in position by the said bolts 6, which pass vertically through holes 10 in the mortised ends. The supercarlines are otherwise horizontally free relative to the roof and may oscillate thereon as may be required by the distortions of the roof in service. The contiguous flanges 18, 19 of 15 each pair of roof sheets are overlaid in a watertight manner embraced and united by seam caps 26 (Figs. 5 and 8). Each seam 20 the supercarline with its sheet flanges 18, 19. At its inner end the side flanges 27 are removed from the seam cap (Fig. 5) leaving its top portion extending in the form of a tongue 28 which is perforated at 29. These 25 tongues of the caps which are in line with each other are lapped at the ridge of the roof (Fig. 4) and are united pivotally with each other and with the roof by the said 30 bolts 6 which pass through the perforations 29. The supercarline 25 does not entirely, under normal conditions fill the space within 35 the pair of L-flanges 18, 19; nor does the pair of L-flanges entirely fill the space within the seam cap, but some play is allowed to the roof sheet flanges between the supercarline and the seam cap. The outer end of 40 the seam cap is properly notched at its corners and portions of the side flanges 27 are bent inward to form end flanges 30 which overlie the outer end of the supercarline. The top of the seam cap is bent 45 down to form a depending end flange 31 perforated at 32 through its lower part. This flange 31 is secured by a bolt 33 which passes through the said perforation 32 and through the fascia and side plate (Figs. 3 50 and 6). Around the perforation 32 is formed an upwardly bent boss 34 which occupies the space between the flange parts 17 of the roof sheets and gives the flange 31 a solid bearing on the fascia, preventing the flange 55 31 from fixedly clamping the roof sheets when the bolt 33 is tightly screwed up. The seam cap 26 may be additionally secured at its outer end by a malleable hood 35 (Figs. 9 and 10) which incloses said outer end. This hood is formed with a flange 36, recessed at 37 on its inner face to receive the 60 parts 31 and 17, and perforated for the bolt 33 and a nail 39 by which the flange is secured to the fascia and side plate. When 65 such hood 35 is employed the end flange 31 of the seam cap may be omitted, or made shorter; or both the flanges 30 and 31 may be omitted, the hood 35 serving to close the outer end of the seam cap. The roof sheets 15 may be additionally se-

cured at the eaves by sheet clips 40 which overlie the top of the sheet (Fig. 10) and are provided with depending flanges 41 perforated for a bolt 42 and nail 43 passing through or into the fascia and side plate. The said bolt 42 and nail 43 are arranged below and do not engage the sheet flange 16. With the clips 40, 41 the bolts 23 may be omitted, or they may pass through suitable perforations in the flanges 41 (Fig. 10). At 70 the ridge of the roof the seam caps are confined by ridge or intersection caps 44 of bent sheet metal or other material having transverse channels 45 to receive the seam caps and also longitudinal channels 46 to receive 75 the interlocked U-flanges of the roof sheets. The intersection cap is perforated for the bolt 6. This bolt also confines the saddle 47 of the running board 48, the said saddle being supported by the supercarlines 25, seam 80 caps 26, and the intersection cap. The end finishing sheet of the roof (Fig. 8) has only one L-flange, its outer end edge being formed with a depending flange 49 which is secured to the end fascia and end plate by staggered 85 nails 50 (Fig. 2).

51 is a malleable end ridge cap inclosing the interlocked U-flanges of the roof sheets at the end of the car, and having a depending flange 52 secured by a bolt 53 to the 90 end fascia and end plate.

In Fig. 12 is shown a modified form of roof sheet side flange 18^a, 19^a and seam cap 26^a, combined with the said subcarline. These flanges may be described as Z-flanges, the part 18^a being inclined upward, backward and outward away from the carline and forming acute angles with the roof sheet and with the flange 19^a, the latter flange lapping over the supercarline. This seam 100 cap has side flanges 27^a which incline downward and inward parallel with the sheet flanges 18^a. By this construction the seam cap is interlocked with the sheet flanges for its entire length against upward disengagement. The supercarline keeps the flanges 18^a, 19^a spaced apart so that the said interlocking arrangement is preserved. Any hood for securing this seam cap 26^a at the 105 eaves of the car, or any intersection cap 110 used with it will be correspondingly modified in shape to properly fit it. The cap 26^a will be applied to the roof sheets and supercarlines in position, by sliding it longitudinally along said parts and then securing its 115 inner end by the bolt 6.

What is claimed is:-

1. In an outside metal car roof, the combination of the top sheathing, supercarlines supported thereon, roof sheets resting on the said sheathing between the supercarlines and having at their sides flanges extending upward and backward at the sides of the supercarlines and having also flanges which lap over the supercarlines, seam caps which 125

- embrace the upwardly and backwardly extending flanges and interlock therewith, and which embrace the supercarlines, and means for securing the ends of the seam caps, substantially as specified. 5
2. In an outside metal car roof, the combination of the top sheathing, supercarlines resting thereon and pivotally connected at their upper ends with the roof and having 10 their middle portions movable longitudinally of the roof as may be required by the movement of the roof sheets, roof sheets resting on the said sheathing between the supercarlines and having at their sides 15 flanges embracing the sides and tops of the supercarlines, seam caps embracing the said flanges and the supercarlines, and means for securing the outer ends of the seam caps, substantially as specified. 20
3. In a car roof, the combination of a supporting frame, supercarlines movably secured at their ridge ends to the said frame, roof sheets having side flanges extending up at the sides of the supercarlines, and seam 25 caps embracing the said side flanges and secured at their ridge ends and at their eaves ends to the roof frame, whereby the roof sheet flanges and the lower part of the supercarlines may oscillate longitudinally of the roof 30 within the seam caps; substantially as specified. 35
4. In a car roof, the combination of a supporting frame, supercarlines fitted together and superposed at their ridge ends, roof 35 sheets having side flanges extending up at the sides of the supercarlines, seam caps embracing the roof sheet flanges and supercarlines and secured at their eaves ends to
- the roof frame, and bolts passing through the seam caps, supercarlines and ridge portion of the roof frame, leaving the lower and outer parts of the supercarlines free to oscillate longitudinally of the car to accommodate the pressure or shifting of the roof sheets; substantially as set forth. 40
5. In a car roof, the combination of roof sheets having Z-flanges at their sides comprising flanges which extend upward and backward at the sides of the supercarlines and flanges which lap over the supercarlines, seam caps embracing and extending under said flanges and secured at both ends to the roof frame, whereby the said parts are interlocked at points between the ridge and eaves against separation, supercarlines 50 within and between the said Z-flanges, and said roof frame; substantially as set forth. 55
6. In a car roof, the combination of a supporting roof frame, roof sheets having side flanges comprising upwardly extending and horizontal portions, supercarlines confined beneath the horizontal portions of the roof sheet flanges and arranged to oscillate thereunder longitudinally of the car, and means for pivotally connecting the ridge ends of 60 the supercarlines with the roof frame so as to allow of the said longitudinal movement of the other portions of the supercarlines; substantially as set forth. 65

In testimony whereof, I have hereunto set 70 my hand in the presence of two subscribing witnesses.

RAYMOND C. DUDLEY.
